UNITED STATES PATENT OFFICE

2,465,242

GAS TORCH

Dale A. Line, Bartlesville, Okla.

Application September 16, 1944, Serial No. 554,448

1 Claim. (Cl. 158—111)

1

The present invention relates to new and useful improvements in gas torches adapted for operation by a source of either natural or artificial gas and has for its primary object to provide a device of this character which may be easily and conveniently attached to a conventional gas stove by removing the burner therefrom, or to a gas hose or any other convenient outlet in the home or work-shop.

An important object of the present invention is to provide a gas torch of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a side elevational view.

Figure 2 is a longitudinal sectional view, and

Figure 3 is a transverse sectional view taken substantially on a line 3—3 of Figure 1.

Referring now to the drawings in detail wherein for the purpose of illustration I have disclosed a preferred embodiment of the invention, the numeral 5 designates a coupling having a threaded end 6 adapted for threaded engagement with the burner connection of a feed pipe of a gas stove (not shown), the coupling also being formed inwardly of its threaded end with spiral ribs 7 by means of which a gas hose may be attached thereto. The other end of the coupling is formed with an enlargement 8 having flat sides adapted for engagement by a wrench to apply or remove the coupling, the enlargement being internally threaded for threadedly receiving an extension 9 on a nut 10, the nut also being internally threaded for threadedly receiving one end of a tube 11, the tube being externally threaded for threaded engagement with one end of a conventional form of hickey 12 having open sides. The tube 11 is adjusted by means of a flange 13 having flattened sides for receiving a wrench.

A nipple 14 is threaded in the outer end of the tube 11 and is formed with a restricted orifice 15 from which gas is discharged for mixing with air entering the open sides of the hickey.

Threadedly attached to the other end of the

2

hickey 12 is a tube 16 having a burner head indicated generally at 17 suitably secured at its upper end. The head 17 includes a tubular portion 18 externally threaded at each end for threaded engagement with inner and outer caps 19 and 20, the cap 19 being secured to the tube 16 and the cap 20 having a burner opening 21 therein. The caps 19 and 20 are formed with circumferentially spaced ribs on the outer surfaces thereof to facilitate the threading engagement thereof with the tube 18. The tube 18 is formed with a plurality of vent openings 23 in the sides thereof and the tube is also formed on its outer surfaces with circumferentially spaced ribs 24.

It is believed that the details of construction and manner of use of the device will be readily understood from the foregoing without further detailed explanation.

Having thus described the invention, what I claim is:

In a gas torch, a tube, means attached to one end of the tube and adapted for supplying air and gas thereto in a mixture, and a burner head on the other end of the tube comprising a tubular portion larger in diameter than said tube and into which said other end of the tube extends part way in spaced detached relation thereto, and end caps on said portion one of which is fitted tightly around and secured to the tube and closes the bottom of said head, the other cap having a single central burner opening therein concentric to said portion.

DALE A. LINE.
